(57) **CLAIM**

The ornamental design for container with hooks for a walker or wheelchair, as shown and described.

DESCRIPTION

FIG. 1 is an isometric view of the container with hooks for a walker or wheelchair with environment showing my new design;

FIG. 2 is an isometric view thereof;

FIG. 3 is a rear isometric view thereof;

FIG. 4 is a front elevational view thereof;

FIG. 5 is a rear elevational view thereof;

FIG. 6 is an isometric view thereof shown with environment;

FIG. 7 is an isometric view thereof shown with environment;

FIG. 8 is a left side elevational view thereof; and,

FIG. 9 is a right side elevational view thereof.

The broken lines represent a portion of the walker which form no part of the claimed design. The screws shown in broken lines in FIGS. 4, 5, 8, and 9 are shown for illustrative purposes only and form no part of the claimed design.
